GEORGE J. H. JACQUES, OF PAWTUCKET, RHODE ISLAND.

KNITTING MACHINE.

Application filed October 13, 1922. Serial No. 594,281.

The object of the invention is to provide a knitting machine of the circular type suitable for producing stockings and garments of similar type with a view to the production of a more elastic fabric with the minimum risk of injury to or disarrangement of the parts of the mechanism and under conditions tending to reduce the responsibility and necessity for the exercise of skill on the part of the operator or attendant; and with these objects in view the invention consists in a construction and combination of parts of which a preferred embodiment is shown in the accompanying drawings, wherein:—

15 Figure 1 is a plan view of a knitting machine showing the general application of a back pick.

20 Figure 2 is an enlarged plan view of a needle cylinder showing the application of the back pick.

Figures 3, 4 and 5 are respectively end, plan and side views of the back pick mechanisms.

25 Figure 6 is a view in side elevation of the raising and lowering cam and the operating means for the same.

Supported by a suitable base or platform 40 is a stationary needle cylinder 41 grooved as in the ordinary practice to form guides 30 for the needles 42 and revolvably mounted in surrounding relation with the base of the cylinder is a cam ring 43.

The cam ring is capable, in the operation of the mechanism, alternatively of a continuous rotary motion in a single direction and an oscillatory or rocking movement alternately in opposite directions and the power necessary to drive said ring is applied through driving mechanism consisting of 35 slow and fast pulleys 47 and 48 traversed by a belt 49 which may be shifted from one to the other and may be actuated by any suitable motor, a driving gear 50 carried by a shaft 51 of the slow pulley 47 and also 40 adapted to be actuated by the fast pulley 48 through intermediate speed multiplying gearing consisting of the gear elements 52, 53 and 54 of which the latter meshes with the gear 50 and which latter communicates

50 motion to a crank gear 55. The cam ring 55 in the construction illustrated is provided with gear teeth 56 with which mesh the teeth of the beveled driven gear 57 carried by the shaft 51, and loosely mounted upon said shaft 51 is an oscillatory pinion 59 actuated by a rack 60 adapted to be oscillated by a bell-crank lever 61 of which one arm is connected by a link 62 to said crank gear 55 and of which the other arm has a slot and pin connection with said rack bar. A 60 clutch 65 is slidingly fitted on the shaft 51 and is keyed thereto and is adapted by its terminal clutch faces for engagement alternatively with the gear 50 and the oscillatory gear 59, so that when the clutch is in one 65 position the cam ring is driven continuously in one direction by reason of the rotation of the shaft 51 and when the clutch is in the other position the cam ring receives an oscillatory or alternately reversed motion 70 through the action of the rack on the gear 59.

In the knitting of stockings and like garments the continuous rotary motion of the cam ring is utilized in the production of the 75 leg portion of the garment and when the heel portion thereof is reached the oscillatory movement of the cam ring is instituted, to be followed by a further operation of the cam ring in a continuous direction to form 80 the foot portion of the garment between the heel and the toe thereof, and again the mechanism is adjusted to return to the oscillatory movement of the cam ring to form the toe portion of and complete the garment. 85

Carried by the cam ring for cooperation with and control of the needles is a stitch cam 66 which is capable of vertical adjustment by means of the screw 109 and check nut 114. The stitch cam has a horizontal 90 movement controlled and operated by a lever 111 and a lock pawl 113. When the lock pawl 113 is raised, it permits springs 112 to pull the stitch cam 66 into position adjacent the needle cylinder. This stitch cam 95 66 is mounted on the cam ring 43 and its direction of rotation is governed by reversing mechanism, as hereinafter set forth. To

withdraw the stitch cam, the lock pawl 113 is first lifted manually from the path of the lever 111 and by manually grasping the knob of the lever 111 and moving it upon its fulcrum, the stitch cam moves from the needle cylinder due to the link connection 111^a with a stud 111^b which is on the carriage 110 which supports the screw 109 and the stitch cam. It will be noted when the lever 111 is operated in this manner, the springs 112 are tensioned so that, when the lever 111 is again released, the springs will move the stitch cam into position adjacent the needle cylinder. At opposite sides of the stitch cam are raise cams 67 and 68 and picks or pick cams 69, and at a diametrically opposite point on the cam ring 43 is a back pick 70 which abuts the needles, two at a time, and operates in both directions as the machine reverses back and forth. The back pick is carried by a pivoted arm 126 which is pulled upwardly, as shown in dotted lines in Figure 5, by spring 127 after the cam 121 revolves, forcing the retaining bar 123 upwardly, releasing pressure on the back pick pivot arm 126, which pressure is caused by the spring 124 which is of greater tension than the spring 127. When the cam 121 again revolves, spring 124 pulls the retaining bar 123 downwardly and this in turn pulls the back pick pivot arm 126 downward and it is allowed to move as indicated by dotted lines (Figure 5). Every time a corner of the cam 121 passes under the foot 122 of the retaining bar 123, the retaining bar 123 raises against the action of the spring 124 and the arm 125 of the retaining bar relieves pressure on the arm 126, allowing the spring 127 to move the back pick arm 126 upwardly to the position in dotted lines. As the back pick 70 swings, it pulls the butts or lateral portions of the needles only part way. On opposite sides of the back pick are located the needle movers 71 and 72 which complete the movements of the needles. This method of moving the needles is gradual rather than sudden, therefore making a more elastic fabric and insuring a longer life for the needle cylinder and needles. At a point between the stitch cam and the back pick and relatively close to the latter at the side thereof occupied by the needle movers 72 is a raising and lowering cam 73. The raise cams 67 and 68 will engage the butts of and raise the needles at a desired moment. A raise cam 73^a is also provided and will raise the long butt needles only and only at such time as the machine is reversing to knit heel and toe, this raise cam 73^a being too far away from the needle cylinder to operate short butt needles. The lowering cam 73 causes long and short butt needles to drop after heel and toe are knitted. These cams 73^a and 73 are moved simultaneously by revolving the cam disk or ratch-

et cam 108 caused by coming in contact with projecting pin 136 (Figure 2) and as hereinbefore mentioned, the cam or operating lever 135 is held against the cam disk or ratchet cam 108 by a spring 134. A spring 140 is used to create friction relative to the ratchet cam or cam disk 108 and prevent it from turning too far when it comes in contact with pin 136. The raised cam 68 is held toward the needle cylinder by means of a spring 68^a and is held in downward working position by spring 68^b. It can be moved in and out radially, as shown. As will be understood, the raise cams 67 and 68 are more or less short and due to their particular construction and their location with respect to the needle cylinder, the short butt needles are incapable of operating.

The timed operation of these different instrumentalities carried by the cam ring, the shifting of the belt to vary the speed of rotation of the cam ring and the shifting of the clutch to change the character of movement of the cam ring from continuous to oscillatory and vice versa is regulated by a controlling mechanism consisting in the construction illustrated of a shaft 74 carrying a ratchet disk 75 with which cooperates a feed pawl 76 carried by an oscillatory lever 77 operatively connected with and receiving its motion from the bell-crank lever 61, the motion of said shaft obviously being step by step. Actuated by a cam disk 80 on the controller shaft 74 is a belt shifting lever 81 between which and the cam there is preferably located a reversing lever 82. Connected with the clutch 65 is a clutch lever 83 which receives its motion through a reversing lever 84 from a cam disk 85 also carried by said controller shaft.

Furthermore carried by said controller shaft is a chain wheel 86 over which extends a tensioned pattern or trip chain 87 provided with trip pins, and arranged in the path of the trip pins of said chain is a trip lever 91 carrying a supporting pin 92 and yieldingly held in its normal position by a spring 93, said supporting pin serving as a means of holding in its inoperative position a pattern pawl 94 in the path of which is arranged a ratchet wheel 95 attached to a pattern drum 96 which is loosely mounted on said controller shaft. When a trip pin of the chain 87 comes in contact with the trip lever 91 and causes a tilting thereof, the supporting pin 92 releases the pattern pawl 94 and permits it to drop into engaging relation with the ratchet 95,—said pattern pawl being carried by the oscillatory lever 77 which, as above described, carries the pawl 76. The pattern drum, which is thus actuated by the pawl 94 at intervals controlled by the location of the trip pins on the chain 87 carries tappet pins 97 in the paths of which are arranged shifting levers 120

- 98 and 99 of the bell-crank type connected by intermediate means such as the links 100, levers 101 and links 102, or the equivalents thereof, with lifting levers 103 and 104 which respectively control stop pins 105 and 106 and serve to raise or operatively dispose said pins with relation respectively to cam disks 107 and 108 which serve as the actuating means respectively for the back pick 70 10 and the raising and lowering cam 73, which are in service when the oscillatory movement of the cam ring is in progress, to properly control the needles of the cylinder in the formation of the heel and toe portions of 15 the garment.

The cam wheel 107 which controls the operation of the back pick is of the star wheel type with a plurality of radial arms 120 for engagement with the stop pin 105 when 20 the latter is moved into its operative position through the actuation of the drum 96, and said cam disk carries a cam 121 upon which rests the foot 122 of a retainer bar 123 hereinbefore described. A friction 25 spring 128 controlled by a screw 129 which forms the spindle of the cam disk 107 serves to hold the latter against an excessive movement or a movement of more than one step when an arm thereof comes into contact with 30 the stop pin 105.

The raising and lowering cam mechanism referred to hereinbefore as shown at 73 and located on the cam ring at one side of the back pick, and including the operating 35 cam disk 108 for actuation through contact with the stop pin 106, consists essentially of the raising cam member 130 and the lowering cam member 131 supported by a carrier slide 132 mounted for vertical movement in 40 a guide 133 and exposed to the yielding lifting action of a contractile spring 134. These cam members are designed for actuating the long and short butt needles when the machine is being reversely operated or the cam 45 ring is being oscillated in the formation of heel and toe portions of the garment, and they are capable of vertical movement with relation to the cam ring by reason of the carrier 132 which is actuated by the cam 50 disk 108 through the operating lever 135 which is provided with a pin 136 riding on the cam face of the said disk 108 of which the substantially radial arms 137 are successively engageable with the stop pin 106. 55 The friction spring 140 is employed in connection with the cam disk to prevent overthrow thereof when an arm 137 comes in contact with the stop pin. Furthermore the lowering cam member consists of a link 60 pivotally connected as at 140' with a carrier arm 131 extending from the carrier slide, and provided at the other end with a guide pin 142 operating in a slot 143 in a bracket arm 144 which is secured to the cam ring. 65 The elevated position of the lowering cam

is indicated in dotted lines in Figure 6, the normal lowered position of said member being indicated in full lines in said figure.

Having described the invention, what is claimed as new and useful is:—

1. In a circular knitting machine of the type having a stationary cylinder with needles carried thereby, a cam ring revolvably associated in surrounding relation with the cylinder at the base thereof, said cam ring being so mounted as to have continuous rotary and oscillatory motions and capable of being actuated by either motion according to predetermined arrangement, the combination with a back pick including a pivoted arm operatively mounted upon the cam ring, the arm being under tensioned, whereby it may lift the back pick, of a device under greater tension than the first tensioning means to lower the back pick arm, whereby the back pick may engage the butts of a plurality of needles and lower them, means for intermittently actuating the tensioned device to insure the two movements of the back pick arm during the oscillatory motions of the cam ring, and a controlling mechanism movable by the driving mechanism in timed relation with the cam ring and having a device for actuating said clutch.

2. A circular knitting machine including a stationary cylinder with needles carried and guided thereby and having a cam ring revolvably associated in surrounding relation with the cylinder at the base thereof, said cam ring being so mounted as to have continuous rotary and oscillatory motions and capable of being actuated by either motion according to predetermined arrangement, the combination with a back pick including a pivoted arm operatively mounted on the cam ring, of opposed counteracting elements operatively connecting with the back pick arm for lowering and raising the arm during the oscillatory motions imparted to the cam ring, the back pick being engageable with butts of a plurality of needles for lowering them at one time, a device operable intermittently for relieving the action of one of said counteracting elements whereby the other elements may raise the back pick arm.

3. A circular knitting machine including a stationary cylinder with needles carried and guided thereby and having a cam ring revolvably associated in surrounding relation with the cylinder at the base thereof, said cam ring being so mounted as to have continuous rotary and oscillatory motions and capable of being actuated by either motion according to predetermined arrangement, the combination with a back pick including a pivoted arm operatively mounted on the cam ring, of spring means for moving the back pick arm upward, a spring ten-

sioned retaining bar operatively mounted in a guide on the cam ring for moving the back pick arm downwardly, whereby the back pick may operatively engage butts of a plurality of needles for lowering the needles, a cam for operative engagement with the retaining bar to actuate the bar and lessen its tensioning means whereby the first tension-

ing means may raise the back pick arm, the two movements of the back pick arm being 10 in synchronism with the oscillatory motions of the cam ring.

In testimony whereof he affixes his signature.

GEORGE J. H. JACQUES.
